[57] **CLAIM**

The ornamental design for a veterinary playset with panels for decoration, as shown and described.

DESCRIPTION

FIG. 1 is a perspective view of the veterinary playset with panels for decoration showing our new design;

FIG. 2 is a perspective view of the playset of FIG. 1 with cardboard backing, collapsed, which shows the panel fold lines;

FIG. 3 is a front elevation view of the playset of FIG. 1; FIG. 4 is a rear elevation view of the playset of FIG. 1; FIG. 5 is a top elevation view of the playset of FIG. 1 with drawer closed and hinged door shut;

FIG. 6 is a bottom elevation view of the playset of FIG. 1 with drawer closed and hinged door shut;

FIG. 7 is a left elevation view of the playset of FIG. 1; FIG. 8 is a right elevation view of the playset of FIG. 1, with drawer extended and hinged door open;

FIG. 9 is a partial front elevation view of the playset of FIG. 1, showing hinged door open; and,

FIG. 10 is a top elevation view of the playset of FIG. 1, showing drawer extended and hinged door open.
